(57) **CLAIM**

The ornamental design for a suppressor heat shield assembly, as shown and described.

DESCRIPTION

FIG. 1 is an exploded, distal-end, top, and left-side perspective view of a suppressor heat shield assembly showing our new design;

FIG. 2 is a top, distal-end, and left-side perspective view showing the suppressor heat shield assembly in assembled form;

FIG. 3 is a top, proximal-end, and right-side perspective view thereof;

FIG. 4 is a distal-end elevational view thereof;

FIG. 5 is a proximal-end elevational view thereof;

FIG. 6 is a left-side elevational view thereof, and of which the right-side is a mirror image;

FIG. 7 is a top plan view thereof;

FIG. 8 is a bottom plan view thereof;

FIG. 9 is a top, distal-end, and left-side perspective detailed view of the heat sink portion of the suppressor heat shield assembly shown in the FIG. 1 exploded view, shown separate and enlarged for clarity of illustration;

FIG. 10 is a top, proximal-end, and right-side perspective view thereof;

FIG. 11 is a distal-end elevational view thereof;

FIG. 12 is a proximal-end elevational view thereof;

FIG. 13 is a left-side elevational view thereof, and of which the right-side is a mirror image;

FIG. 14 is a top plan view thereof;

FIG. 15 is a bottom plan view thereof;

FIG. 16 is a top, distal-end, and left-side perspective detailed view of the outer shield portion of the suppressor heat shield assembly shown in the FIG. 1 exploded view, shown separate and enlarged for clarity of illustration;

FIG. 17 is a top, proximal-end, and right-side perspective view thereof;

FIG. 18 is a distal-end elevational view thereof;

FIG. 19 is a proximal-end elevational view thereof;

(Continued)

FIG. 20 is a left-side elevational view thereof, and of which the right-side is a mirror image;
 FIG. 21 is a top plan view thereof;
 FIG. 22 is a bottom plan view thereof;
 FIG. 23 is a distal-end and left-side perspective detailed view of the mounting bracket portion of the suppressor heat shield assembly shown in the FIG. 1 exploded view, shown separate and enlarged for clarity of illustration;
 FIG. 24 is a proximal-end and left-side perspective view thereof;
 FIG. 25 is a distal-end elevational view thereof;
 FIG. 26 is a proximal-end elevational view thereof;
 FIG. 27 is a left-side elevational view thereof, and of which the right-side is a mirror image;
 FIG. 28 is a top plan view thereof; and,
 FIG. 29 is a bottom plan view thereof.
 The broken lines showing the screw features in FIGS. 2-4 and 6-8 are included for the purpose of illustrating environmental structure and form no part of the claimed design.
